UNITED STATES PATENT OFFICE

137,716

DESIGN FOR A TOY ALLIGATOR

Jean O. Reinecke, Oak Park, Ill., assignor to The Firestone Tire & Rubber Company, Akron, Ohio, a corporation of Ohio

Application December 31, 1943, Serial No. 112,143

Term of patent 7 years

(Cl. D34—15)

To all whom it may concern:

Be it known that I, Jean O. Reinecke, a citizen of the United States, residing at Oak Park, county of Cook, and State of Illinois, have invented a new, original, and ornamental Design for a Toy Alligator, of which the following is a specification, reference being had to the accompanying drawing, forming part thereof, in which:

I claim:

The ornamental design for a toy alligator, as shown.

JEAN O. REINECKE.
